[57] CLAIM

The ornamental design for a toy rabbit animal figure, as shown and described.

DESCRIPTION

FIG. 1 is a side elevation of a toy rabbit animal figure showing my new design, the opposite side being a mirror-image thereof;

FIG. 2 is a top plan view thereof;

FIG. 3 is a front elevation thereof;

FIG. 4 is a rear elevation thereof;

FIG. 5 is a bottom plan view thereof; and

FIG. 6 is a bottom plan view of an alternative embodiment, the other views being the same as in FIGS. 1-4.
